US00D562067S

(12) **United States Design Patent** (10) **Patent No.:** **US D562,067 S**
Albini et al. (45) **Date of Patent:** **** Feb. 19, 2008**

(54) **SLIPRING PIECE FOR USE IN A POWERED TAP ASSEMBLY**

(75) Inventors: **Martin Albini**, Bozeman, MT (US); **Thomas J. Wernikowski**, Bozeman, MT (US); **Paul Daniel Fichter**, Seattle, WA (US); **Christian P. Burrows**, Tacoma, WA (US)

(73) Assignee: **VolTap, LLC**, Bellevue, WA (US)

(**) Term: **14 Years**

(21) Appl. No.: **29/269,880**

(22) Filed: **Dec. 11, 2006**

(51) **LOC (8) Cl.** **07-01**

(52) **U.S. Cl.** **D7/398**

(58) **Field of Classification Search** D7/313, D7/368, 387, 392, 392.1, 395, 396.2, 397, D7/398, 300; D6/512, 553; D9/434, 435; D23/233, 238, 242, 213, 249, 255, 262; 222/222, 222/255, 481, 568, 566, 569; D13/148, 120; D8/29, 36, 349, 354, 367; 439/416, 725, 439/730, 750, 864, 868, 877, 884

(57) **CLAIM**

The design for a slirping piece for use in a powered tap assembly, as shown and described.

DESCRIPTION

FIG. 1 is a perspective view showing our new design for a slirping for use in a powered tap assembly.

FIG. 2 is an alternative perspective view of our new slirping for use in a powered tap assembly.

FIG. 3 is a top view of our new slirping for use in a powered tap assembly; and,

FIG. 4 is a side view of our new slirping for use in a powered tap assembly.

The broken lines are provided for illustrative purposes only and form no part of the claimed design.
